COMPUTING COUNTER

Edward A. Slye, East Hartford, Conn., assignor to
Veeder-Root Incorporated, a corporation of
Connecticut

Application June 17, 1937, Serial No. 148,718

11 Claims. (Cl. 235—144)

My invention relates to computing counters. It has among its objects to provide an improved cost and quantity counter for use in dispensing gasoline or the like, and adapted to cooperate with a meter and a suitable cost variator as described and claimed in my copending application Serial No. 716,696. A further object of my invention is to provide such an improved counter having improved controlling mechanism associated with the reset operating mechanism and of the type described and claimed in my copending application Serial No. 132,275. Another object is to provide improved controlling mechanism for preventing inaccuracies in the count due to resetting and including improved means for controlling the counter drives and improved means for controlling the number wheels of the several counters which are driven by said drives and the resetting mechanism. Still another object is to provide improved driving connections for the several counters operative during counting and improved reset driving mechanism operative during resetting, whereby these drives are materially improved and simplified. Still further objects of my invention include the provision of improved bodily removable counter units cooperating in an improved manner with these improved counting and resetting drives, as well as the provision of an improved arrangement of the controlling mechanism and the counting and resetting driving mechanisms relative to one another and having the counting and resetting driving mechanisms disposed in an improved manner on the same side of a supporting frame, whereby, while the several counters are operatively connected to their counting and resetting drives in an improved manner, the several counting mechanisms are readily removable or substitutable as units. A still further object of my invention is to provide such improved removable counting units having improved counting and reset driving connections thereon and improved means for enclosing and protecting the counter wheels while permitting counting and resetting operations thereof and ready access to the enclosed mechanism. Another object is to provide such units having improved shutter mechanism forming a part of the units and removable therewith. Still another object is to provide improved operative connections controlled in an improved manner by the cam of the controlling mechanism and controlling and positively operating the shutters on the several counter units in each direction. These and other objects and advan-

tages of my improved construction will, however, hereinafter more fully appear.

In the accompanying drawings, I have shown for purposes of illustration two embodiments which my invention may assume in practice. 5

In these drawings:

Fig. 1 is a front elevation of a counter constructed in accordance with my improvements, certain elements being shown in dotted lines through the side of the frame to facilitate illustration; 10

Fig. 2 is a top plan view of the construction shown in Figure 1;

Fig. 3 is a rear elevation of the structure shown in Figure 1; 15

Fig. 4 is an end view of the structure shown in Figure 1 as seen from the left;

Fig. 5 is a view similar to Figure 1, but with portions of the frame broken away on each side to show the counter units and the shutter mechanism, the latter being shown in closed position and the controlling mechanism being shown in a different position from that shown in Figure 1, i. e. in process of resetting; 20

Fig. 6 is a sectional view on line 6—6 of Figure 2 and showing with parts of the controlling mechanism, the counter units and the resetting and shutter operating mechanism therefor, certain parts of the counter units being broken away to facilitate illustration; 25

Fig. 7 is a sectional view on line 7—7 of Figure 1, showing the brake and clutch mechanism in side elevation in the position thereof occupied thereby during counting; 30

Fig. 8 is a sectional view on line 8—8 of Figure 1 and showing in vertical section the mechanism shown in Figure 7; 35

Fig. 9 is a view similar to Figure 7, but showing the brake and clutch mechanism in the position thereof occupied during resetting; 40

Fig. 10 is a simplified view of the gearing included in the resetting train for the several counters, the view being taken on line 10—10 of Figure 2 and the other mechanism being omitted to facilitate illustration; 45

Fig. 11 is a view substantially on line 11—11 of Figure 1, showing the counter units in plan, the controlling mechanism being omitted to facilitate illustration; 50

Fig. 12 is a perspective view of one of the right hand counter units, herein a cost counter unit;

Fig. 13 is a like perspective view of one of the left hand counter units, also a cost counter unit;

Fig. 14 is a detail perspective view of the clutch 55

and brake operating bell crank and its connections;

Fig. 15 is a detail perspective view of the stop block engaging rebound preventing mechanism;

Fig. 16 is a partial vertical sectional view of one of the counter units when mounted on the frame;

Fig. 17 is a sectional view on line 17—17 of Figure 16;

Fig. 18 is a sectional view on line 18—18 of Figure 16;

Fig. 19 is a sectional view on line 19—19 of Figure 16;

Fig. 20 is a simplified front elevation of a modified form of controlling and shutter operating mechanism, the shutters operated thereby being in open position;

Fig. 21 is a top plan view of the mechanism shown in Figure 20, and

Fig. 22 is a view similar to Figure 20, but showing the mechanism thereof in a different position, with the shutters in closed position, the quantity counters being omitted to facilitate illustration.

In both illustrative embodiments of the invention, it will be noted that the counter construction is shown without a variator, the present improvements being confined to the counter mechanism. It will, however, be understood that in use, the cost computing counters are operatively connected to a variator, and that the quantity or gallon counters are driven from a meter, while the counter cooperates with and controls the drives of both during resetting to insure an accurate count and agreement between the cost and quantity counters, all in a usual manner in this art.

In the form of my invention illustrated in Figures 1 to 19, it will be noted that the counter mechanism is mounted on an upright frame member 1 having a reset operating shaft 2 projecting from what will hereinafter be referred to as the front face thereof, a usual operating connection 3 being provided on one or both ends of this shaft. Herein, also, it will be noted that counter units, removable as complete entities and generally indicated at 4 and 5, are carried on the back face of the frame member 1, the cost, or upper, counter units being indicated at 4 and the quantity or gallon units, or lower, being indicated at 5. Of these, the cost counter units 4 are driven from a variator (not shown) through improved driving connections including a shaft 6, and hereinafter described, while the quantity counter units 5 are driven from a meter (not shown) through improved driving connections including a shaft 7 and also hereinafter described. Further, it will be understood that both sets of counters 4 and 5 are reset by rotation of the reset shaft 2 through improved controlling and operating mechanism, hereinafter described, and that shutters 4', 5', carried on the cost and quantity counter units, respectively, are also controlled and operated by the controlling and operating mechanism mentioned.

Referring more particularly to the cost counter drive, which is operative during counting, note that the variator driven shaft 6 extends upward above the variator and between the sets of right and left hand units 4, 5, and near the rear ends thereof. The upper end of this shaft 6 is journaled in an arm 10 projecting rearwardly from a narrow, centrally located auxiliary frame member 11, likewise upstanding and disposed on a suitable support (not shown) in rear of the main

frame member 1 and in spaced relation to the latter. Herein, this frame 11 is suitably connected to the frame 1 by a plurality of rearwardly extending spacing and connecting rods 12 and 13 connected, respectively, between the frame 1 and oppositely laterally extending arms 14 and 15 on the frame 11 and located substantially midway between the ends of the latter. Further, it will be noted that the shaft 6 is connected by beveled gearing 16, beneath the arm 10, with a transverse counter driving shaft 18, journaled at 19 and 20 in the frame members 11 and 1, as shown in Figure 8. Further, on this shaft 18, a suitable clutch connection is provided which controls the connection between the shaft 18 and the counting mechanisms in both of the cost counter units 4, the construction being such that these counting mechanisms are driven from the shaft 18 during counting and disconnected from this shaft during resetting, as hereinafter described. This clutch comprises cooperating elements 21 and 22, herein friction elements, of which the member 21 is fixed to the shaft 18 at 23, while the member 22 is freely rotatable on that shaft and provided with a spring pressed shipper collar 24, abutting the member 22 during counting under action of a coiled spring 25 on the shaft 18 and which acts between a flange on the collar 24 and an abutment collar 26 fixed at 27 to the shaft 18, just inside the bearing 19. Thus, the construction is such that the clutch elements 21, 22 are normally connected during counting, and during resetting permitted to separate, by shifting the shipper 24 to the right, as shown in Figure 9. Here it will also be noted that the clutch element 22 is provided on its periphery with both a front located larger gear 28 and a rearwardly located smaller gear 29 which form the driving elements for the left and right hand cost counters 4, respectively, as shown in Figure 2. Of these, the gear 28 is connected to an intermediate gear 30 journaled at 31 in spaced relation to the rear face of the frame member 1 and meshing with the driving gear 32 for the counting mechanism of the left hand cost counter unit 4, in such manner as to drive this counter in a well known manner whenever the clutch elements 21, 22 are connected. The other smaller gear 29 on the clutch element 22, in turn, meshes with an intermediate gear 33 fixed to a shaft 34 parallel to the shaft 18, which shaft 34 is suitably journaled at its front and rear ends in bearings 35 on the opposite ends of the right hand cost counter unit 4, and also has a gear 36 on its rear end meshing with a driving gear 37 for the counting mechanism of that counter unit. Here it will also be noted that, while the gear 29 is smaller than the gear 28, the gear ratios between the gears 28 and 32 and the gears 29 and 37 are such that the number wheels of both counter units 4 are driven at the same speed. Thus, the counting mechanisms of the left and right hand cost counter units 4 will be driven from the variator through the shaft 6 whenever the clutch elements 21, 22 are connected, i. e. during counting, and this drive will be disconnected whenever these clutch elements are disconnected, as during resetting, as herein-after described.

Referring next to the driving mechanism for the quantity or gallon counter mechanisms in the gallon units 5, it will be noted that this mechanism is generally similar to that heretofore described, and also driven and controlled in generally the same manner as the cost counter mechanisms. More particularly, the meter driven

shaft 7, also located between the right and left hand units but in front of the shaft 6, drives the shaft 40 through bevelled gears 41, this shaft 40 corresponding to the shaft 18 and being located 5 parallel thereto and the same distance below the reset shaft 2 that the shaft 18 is above the latter, and similarly journaled in journals 19, 20 in the frames 11 and 1. Also, the connection of shaft 40 to the counting mechanisms of the 10 quantity counters 5 is controlled through a like clutch comprising elements 42 and 43. These correspond to the elements 21 and 22 heretofore described and are similarly controlled by a shipper 44, corresponding to the shipper 24, a 15 coiled spring 45, corresponding to spring 25, and likewise acting between the shipper 44 and collar 46, fixed to the shaft 40 and corresponding to abutment 26. Here also, gears 47 and 48 are provided on the element 43, corresponding to the 20 gears 28 and 29. Of these, the gear 47 meshes with an intermediate gear 49, corresponding to the gear 30 and similarly mounted and meshing with a driving gear 50 of the counting mechanism 25 of the left hand quantity counter unit 5, while the gear 48 meshes with an intermediate gear 51 carried on a shaft 52 journaled at 53 at the opposite ends of the right hand unit 5 and carrying a gear 54 which meshes with the driving gear 55 of the counting mechanism of that unit. Thus, 30 the counting mechanisms in the left and right hand quantity counter units 5 will also be driven from the meter through the shaft 7 during counting, i. e. when the clutch elements 42, 43 are connected, and have their drives interrupted during 35 resetting when these clutch elements are disconnected.

Operatively associated with the cost and quantity controlling shippers 24 and 44, is improved mechanism for disconnecting the clutches and 40 braking the drives of both the cost counters and the quantity counters when the reset shaft 2 is rotated to effect resetting. This mechanism includes a shipper operating member 60 slidable without cramping on the shaft 2 and extending 45 upwardly and downwardly therefrom and provided with bifurcated shipper operating arms 61 on its extremities extending around and engageable with the usual flanges on the hubs of the shipper members 24, 44 to form yoke connections 50 adapted to move these members 24 and 44 simultaneously to the right on their shafts 18 and 40 (Fig. 8) whenever the reset shaft 2 is rotated to effect resetting. Herein, this movement is effected through rounded cams 62 provided on 55 the member 60 on opposite sides of the shaft 2 and engageable by cooperating cam members on a forked arm 63 comprising one arm of a bell crank 64. This bell crank is, in turn, fixed to a transverse shaft 65 journaled at its opposite ends 60 at 66 in rearwardly extending projections 67 on the main frame member 1, and herein the bell crank is of the built up type and connected by the shaft 65 by having separate arms pinned thereto (see Fig. 14). The rearwardly extending 65 arm of the bell crank 64 is also connected through an upwardly extending link or rod 68 which at its upper end is pivotally connected to an arm 69 extending parallel to the shaft 65 and fixed to a brake and clutch operating shaft 70. This shaft 70 is journaled at its rear end at 71 at the top of the auxiliary frame 11 and journaled at its front end at 72 in the main frame 1, while the front end of the shaft projects through the latter frame and is connected to controlling and 70 operating mechanism operative during resetting 75

and hereinafter described. Thus, when the shaft 70 is rotated to lift the arm 69, the bell crank 64 will be pulled upward about its axis 65, in such manner as to cause its cam carrying arms 63 to engage the cams 62 on the clutch shipper operating member 60, and thereby move the latter member rearwardly longitudinally of the shaft 2 to reciprocate the shippers 24 and 44 rearwardly on their shafts 18 and 40, respectively, to elements 22 and 43 and thereby free 19 the latter for rotation during resetting, relative to their cooperating clutch elements 21, 42.

Here attention is also particularly directed to the fact that before clutch elements 22 and 43 of the cost and quantity counter drive clutches 13 are disconnected from their cooperating elements 21 and 42, the drives for both elements 22 and 43 are simultaneously braked. This is due to the fact that the shafts 18 and 40 are slightly shiftable longitudinally in their bearings, and the further fact that, as the shippers 24 and 44 are moved rearward by the member 60, the springs 25 and 45 are compressed against the abutment collars 26 and 46 fixed to the shafts 18 and 40, in such manner that these collars move with the shafts and press against their adjacent journal portions 19, 19' on the frame 11 in such manner as to provide a simple yet very effective brake. Accordingly, it will be noted that, although the clutch elements 22 and 43 are thus freed by their disconnection from the elements 21 and 42, in such manner as to permit rotation during resetting of the gears 28, 29 and 47, 48, which are connected to the several counter driving gears as heretofore described, the shafts 18 and 40 are braked in such manner as to prevent their rotation with the elements 22 and 43. Accordingly, rotation of these shafts 18 and 40 in such manner as to insert backlash in the drives of the several counters 4, 5, and backlash which 49 would have to be taken up in the next counting operation, and thereby inject error into the next counting operation, is effectually prevented. Further, it will be noted that while the drives are thus braked, the rotatable clutch elements 22, 45 43 are left entirely free as shown in Figure 9 so as to reduce the load on the shaft 2 and the consequent effort required of the operator during resetting; the shipper members 24, 44 then having their hubs moved out of contact with the hubs of the clutch elements 22, 43 by the same movement which shifts the shafts 18, 40 longitudinally to cause the collars 26, 46 to move into braking engagement with the frame. It will further be noted that these collars provide a substantial area in contact with the ends of the journals 19, 19' in braking position, in such manner as to provide an effective braking action under the action of their springs 25, 45.

Cooperating with the clutch shipper and brake 60 applying mechanism just described, is improved controlling mechanism. This mechanism is of the general type described and claimed in my previously mentioned application Serial No. 132,275, and likewise located in the same position, 65 i. e. on the outside or front face of the frame, herein the upstanding frame member 1. Thus, at this point, it is sufficient to state that this control mechanism includes a cam member 73 adapted to be rotated about a pivot 74 from the 70 position shown in Figure 1 to the position shown in Figure 5 at the beginning of resetting, and having means for causing it to remain in the latter position during the remainder of the resetting operation of the reset shaft 2, and then to 75

be returned to its initial position by a coiled spring 75 connected between the frame 1 and an extension 76 on the upper end of this cam member. Here, however, it will be noted that a clutch and brake operating arm 77 is provided which has a collar 78 fixed to the front end of the shaft 76 which protrudes through the frame 1, this arm 77 also having a forwardly extending pin 79 on its free end which is adapted to be disposed during counting in a notch 80 in the cam member 73 and to ride out of the notch and to be cammed out of the same by a cam surface 81. Thus, as the member 73 starts to move at the beginning of resetting, from the position shown in Figure 1 to that shown in Figure 5, this pin 79 moves out of the notch 80 and during the remainder of resetting rests on a dwell surface 82 on the edge of the member 73, as shown in the latter figure. It will accordingly be clear that the clutch elements 22 and 43 for both the cost and quantity counters will be disconnected, and that the variator and meter driven drives will be braked by the collars 26 and 46, both immediately following the initiation of resetting, and that the parts will be held in these positions during the remainder of resetting and until, through mechanism hereinafter described, the cam member 73 is moved reversely to permit the pin 79 to reenter the notch 80, which return occurs after the counter wheels have been returned to zero and at the end of the operation of the controlling mechanism including the cam member 73.

This controlling mechanism, since it is essentially similar to that in my previously mentioned application, need not be specifically described herein. It should, however, be noted that while the member 73 is of somewhat different shape from that in that application, and, although the same in both its counting and resetting positions is disposed at slightly more of an angle to the left than as previously shown, the function of this cam member is essentially similar to that previously described. The pin 83 therein and the cam surfaces 84, 85 and 86 thereon also similarly cooperate, respectively, with the rotating cam 87 rotatable with the shaft 2 and having the notch 88 therein, and with the pivoted spring biased latch 89 having a pin 90 engaging the cams 84, 85, 86. The same is also true of a pin or projection 91 on the latch 89 and which similarly cooperates with a plurality of latch faces 92, 93 on a spring biased non-return pawl 94, also similar to that previously described. The latter also has arms 95 and 96 similarly cooperating with the ratchet member 97, which member 97 is also rotatable with the reset shaft 2 and likewise generally similar in function to the like ratchet member in my previously described mechanism as regards its ratcheting and camming functions, while also having a like pawl 98 adapted to cooperate therewith and with the non-return pawl 94, as in my prior case. Further, it will be evident that the operation of this control mechanism will be generally similar to that in my previously mentioned application. Thus, it is believed sufficient to say that undesirable reversals of the reset operating shaft 2 during resetting are thereby prevented, while requiring the latter shaft to be rotated through more than a complete revolution to effect resetting and obtaining initial and final 45° movements of the counter reset shafts, all in such manner as to insure the return of all wheels of the units 4, 5 to zero position, herein through an

improved reset driving train connected between the shaft 2 and the several counter mechanisms.

This improved reset operating train is herein disposed between the frame 1 and the counter driving trains which are operative during counting, and carried on the rear face of the frame 1. As shown, herein each counter mechanism in the several units 4 and 5 comprises a plurality of operatively connected counter wheels having a coaxially disposed reset operating shaft 100 provided with a usual resetting groove 101 and adapted to cooperate with usual spring pressed pawls 102 in the several counter wheel units. Further, it will be noted that the front ends of the several shafts 100 in the cost counters, have resetting gears 103 fixed thereto, while the like ends of the resetting shafts 100 in the quantity counters have gears 104 connected thereto, while all of these gears are rotated from a gear 105 fixed to and rotatable with the reset shaft 2. More particularly, gears 106, above and below the gear 105, mesh therewith and these gears 106 drive the gears 103 or the gears 104 through intermediates 107. Accordingly, when the resetting shaft 2 is rotated, and while the clutch elements 22 and 43 are disconnected and the braking collars 26 and 46 are disposed in braking position, the several resetting trains will be rotated from the gear 105 in such manner as to rotate the several gears 103 and 104 and thereby rotate the several resetting shafts 100 to bring all of the number wheels back to their zero positions in a well known manner. Further, it will be evident that, as in my application mentioned, I also obtain through the controlling mechanism above described and the action of the spring 75 on the cam member 73, a final reverse rotation of the several shafts 100 through an angle of 45°, in such manner as to insure the return of all of the counter wheels to their zero positions as a result of a single resetting operation of the shaft 2.

Operatively associated with this resetting mechanism is also means cooperating with the driving and resetting trains of the several counters for preventing overthrow of the counter wheels when the same are returned to zero. This mechanism also is generally of the construction described and claimed in my above mentioned applications in that it includes counter overthrow stopping blocks and a swinging cooperating stop arm movable in timed relation with the resetting mechanism and into the paths of these blocks to stop the lowest order wheel of each counting mechanism in zero position. However, herein these blocks, shown at 110, are provided on the gears 28 and 47, which gears are herein carried on the clutch members 22 and 43 and form a part of the counter wheel drives during counting and also are rotatable with these clutch elements 22, 43, relative to the shafts 18 and 40 and the clutch elements 21, 42, during resetting. Herein, moreover, it will be noted that these blocks are located in a different position, i. e. on the front faces of the gears 28, 47 and just outside the outer periphery of the cooperating clutch elements 21, 42. As heretofore, I also provide a swinging block engaging arm 111, herein adapted to cooperate with the blocks 110 on both gears 28, 47 and journaled on the reset shaft 2 on a rotating collar 112 between a collar 113, fixed to the shaft and having fixed thereto the gear 105, and a collar 114 fixed to the shaft 2 and disposed between the arm 111 and the reciprocable clutch operating member 60. Also, as in my previous applica-

tion Serial No. 132,275, I provide a pin 115 on the upper arm of the member 111 and received in a slot 116 in a link 117, which link is pivoted at 118 on the arm 96 of the non-return pawl 94 and has a coiled spring 119 connected between the pin 115 and the pivot 118. Thus, it is possible to actuate the swinging arm 111 to cause it to move into the path of the blocks 110, and thereby stop the counter resetting trains through 10 stopping the gears 28, 47 which are geared to the lowest order number wheels of the several mechanisms, the member 111 also being thrown out of the path of the blocks 110 in the same manner as described in my above mentioned application. 15 Operatively associated with the above described mechanism is also improved mechanism for preventing rebound of the gears 28, 47 carrying the blocks 110, which might otherwise occur during resetting rapidly. This mechanism includes rebound controlling means associated with the block engaging arm 111 and operative to engage the blocks 110 on the opposite side of the latter from the member 111. Herein, these means are in the form of a swinging lever 120 pivoted on the 20 shaft 2 and lying next the arm 111 and provided with offset block engaging hooked ends 121 which lie in the plane of the member 111 and herein are suitably carried on the member 120 in such manner as to engage the edges 122 of the blocks when 25 the ends of the arm 111 engage the opposite edges 123 of the blocks. Further, it will be noted that this rebound controlling member 120 is herein provided with an extension 124 between its pivot and its upper end 121, which extension is connected by a coiled spring 125 to any suitably located abutment, herein the shaft carrying the gear 30. As a result of this construction, the ends 121 on the member 120 will normally ride on the periphery of the clutch elements 21, 42 during 30 counting, the blocks 110 then forcing these ends out of their path as the connected clutch rotates. When, however, the clutch elements 22, 43, carrying the blocks 110, are rotated in the same direction during resetting, the blocks 110, after forcing 35 out the ends 121, have their surfaces 123 engage the ends of the arm 111, thereby stopping the blocks. Thereupon the spring 125, which is then under tension, snaps the hooked ends 121 back into engagement with the faces 122 of the blocks 40 110 in such manner as to cooperate with the member 111 in securely holding the blocks 110 against movement in either direction until the arm 111 is thrown out by the link 117 at the end of the resetting operation. Moreover, attention is directed to the fact that even after the arm 111 is 45 thus disengaged from the block surfaces 123, the ends 121 cooperate to hold the blocks 110 against reverse movement, although the blocks may then at any time resume rotation when counting is 50 resumed.

The counting mechanisms on the several units 4 and 5, shown in Figures 16 to 19, are also provided with means for preventing the overthrow of the several counter wheels 130, 131 and 132 of each unit during resetting. These counting mechanisms are of the general construction described and claimed in my copending application, Serial No. 716,696 and are the same on the several units, so that a detailed description is unnecessary and a showing of one will suffice for all. Referring to Figure 16, it will be evident that the lowest order wheel 132 thereof will be stopped by the controlling mechanism for the block 110 just described and including the member 111 and 55 hooked ends 121, acting on the driving train of

this gear. Further, it will be noted that the wheel 132 carries a two toothed gear 133 on its opposite face adapted to cooperate with a spring pressed pawl 134 carried on the next higher order unit, with the pawl abutting against a projection 135 on the wheel 132 in such manner as to cause the wheel 131 to stop in its zero position when this pawl engages this projection. Thus, with the pawl 134 carried on a plate 136 keyed to the sleeve 137 of the unit 131, the latter unit is positively stopped in zero position, while, a similar mechanism being provided between the unit 131 and the next higher order unit 130, the latter unit will also be stopped in zero position. Here also it will be understood that each of the units is of a usual construction having a slot 138 in its sleeve 137 and a spring pressed pawl 102 movable through this slot into the groove 101 in the reset shaft 100, while a usual clutch mechanism, including a toothed ratchet member 140 10 acted upon by a plurality of spring pressed pawls 141 in a usual manner, is also provided on each of the units 130 and 131 and acts to connect the twenty toothed driving gears 142 to the number wheels. Here attention is, however, directed to 15 the fact that, as distinguished from the external transfer counting mechanisms shown in my prior applications, the transfer mechanism herein is of the internal transfer pinion type and of the general construction described and claimed in the 20 Spaunburg application, Serial No. 148,719, filed herewith, with transfer pinions 143 mounted on upstanding partition carrying members or plates 144, herein suitably apertured at their opposite ends at 145, and mounted and positioned by means 25 of spacing sleeves 146 on the two rear connecting bolts of the counter units 4 and 5, hereafter described.

Referring more particularly to these counter units 4 and 5, it will be noted that these are also 30 of an improved construction including opposite rectangular end plates 150 and 151 having suitable hub portions providing journals for the reset shaft 100 and connected at their corners by bolts 152 to form a unitary frame. These bolts 152 at their front ends are connected to the main frame 1. Herein, cap screws 153 are extended through the frame and are connected to the front ends of the bolts 152 by spacer nuts or sleeves hereafter described. As shown, these cap screws are 35 removable from the front of the frame 1 to permit the counter unit to be removed rearwardly as an entirety upon removal of these screws, while nuts 154 are also provided on the opposite ends of the bolts to permit access to the counter wheels upon removal of the end plates 151. Herein, 40 spacer nuts or sleeves 155, into which the bolts 152 and cap screws 153 are threaded from opposite ends, are also provided between the front end plate 150 and the frame 1 to space the unit rearwardly 45 from the frame 1, while also permitting lateral removal of the unit if desired, while providing space for the reset driving gear of the unit, shown for example in Figure 16, as the gear 103, which gear is fixed to the shaft 100 by usual adjusting means 156. Here it will also be noted that the 50 number wheels 130, 131, 132 are enclosed in and protected by a casing 157, herein in the form of a single casing member of sheet metal open at each end and fitting on the end plates 150, 151. 55 As shown, the end edges of the casing 157 are positioned in kerfs 158 formed on the outer corners of the end plates 150, 151 and the casing is provided with curved portions 159 received in these kerfs and definitely positioned thereby and 60

extending in opposite directions down to a window 160 in the form of a longitudinal slot between the portions 159, while the remainder of the casing is of substantially rectangular cross section. 5 On the tops and bottoms of the casing, the latter is also provided with projections 161 received in slots 161' in the end members 150, 151 and the back of the casing is also provided with cut-away portions 162 through which the intermediate drive gears may extend. Here also note that on the right hand cost and quantity units 4, 5, one of which is shown in Figure 12, bearings 35, 53 for the shafts 34, 52 carrying the intermediate gears, are provided on the end plates 150, 151 of 10 said units, while on the left unit of each set, one of which is shown in Fig. 13, a cut-away portion 163 is provided in the end plate 151 to receive the support for the intermediate gears 38, 49. It will also be observed that a pair of cost counter units, 15 shown in Figs. 12 and 13, is provided, of which the right hand unit carries the shaft 34 and the intermediate gears 33, 36 so that these gears and shaft are removable with the unit, while the left hand unit has no such gears and shafts connected thereto, the intermediate gears 38, 49 there being carried by the frame 1 and remaining upon the latter while the unit is removed. The same is also true of the right and left hand quantity counter units 5, which, apart from the numbering 20 of the wheels, are the same as the cost counter mechanism. All of these units may thus be readily removed bodily by removing the cap screws connecting the several units to the main frame 1, while each also may be readily taken down for access to the counting mechanism therein, by simply removing the rear end plate 25 and removing the casing enclosing the counter wheels.

In my improved construction, each of the units 4 and 5 also includes a shutter, the shutters for the cost units being indicated at 4' and for the quantity units at 5' (Figure 5). Herein, each of these shutters is in the form of an oscillating shutter pivotally mounted on the reset shaft 100 30 between the end frames 150, 151 and the end number wheels. In this construction also, means are provided for insuring the operation of these shutters in timed relation to the resetting mechanism, so that, while the shutters 4', 5' are open during 35 counting, the same are closed immediately upon the initiation of resetting and maintained closed until the several counter wheels 130, 131, 132 have all been returned to zero, whereupon, as the cam member 73 is returned to its initial position by 40 the spring 75, the shutters are all simultaneously opened. Herein, this mechanism is so associated with the cam member 73, that the several shutters are actuated by this cam member to close at the beginning of resetting and permitted to 45 open as reset shafts 2 and 100 move through their final 45° reverse movement at the end of the resetting operation. This actuation and control by the cam member 73 is herein obtained by connecting 50 improved shutter operating mechanism to the shaft 70 which actuates the clutch and brake mechanism, and which is, in turn, actuated by the pin 79 engaging in the notch 80 in the cam member 73 and riding over the cam surface 81, with 55 lost motion on the dwell surface 82 during the intermediate portions of the resetting operation. More particularly, a shutter operating arm 170 is disposed between the train of reset gears, operative during resetting, and the train of counter 60 driving gears, operative during counting, as shown

in Figure 2, and this arm extends to the left and downward, as shown in Figure 5.

Here attention is particularly directed to the disposition of the notch 80 and to the shape of the cam surface 81 which while positively operating the brake and clutch operating mechanisms, also positively moves the pin 79 into the shutter closing position of the shutter operating arm 170, and to the shape of the opposite cam surface 81a which is such as not only to positively release the 10 brake and clutch operating mechanism, but also to move this arm 170 and the shutters operated thereby, positively into open position. Thus, it is not only possible to use the pin 79 required for the brake and clutch mechanism, but to obtain a positive shutter movement in each direction in such manner as to obviate the need of a spring on the arm 170. Moreover, it will be observed as a result of this construction, it is made possible to utilize the lost motion connection between the cam member 73 and the brake and clutch as a needed lost motion connection between the cam member 73 and the shutters, thereby enabling the latter to be operated through their desired short range and also be operated quickly, without increasing the range of movement thereof despite the long 45° reverse movement of the rotating cam 81.

As illustrated in Figure 5, this shutter operating arm is also connected to the shutters in an improved manner. As shown, the free end of the arm is connected to the left hand cost counter shutter 4', herein through a slot 171 on the extremity of the arm and a pin 173 on an upwardly inclined projection 172 on the shutter projecting in back of the shutter pivot. The shutter being disposed inside the end wall of the counter unit, an arcuate slot 173' is provided in the end wall 150 thereof to permit opening and closing movement of the shutter as the pin 79 moves as previously described in connection with the operation of the clutch and brake mechanism. Further, the protruding end of the pin 173 is connected by a link 174 with a similar pin 175 carried on the shutter 5' of the left hand quantity counter unit, which pin moves through a slot 176 corresponding to the slot 173' (Figure 6). This lower left hand shutter 5' also is provided with another angularly disposed arm 175' carrying another pin 177 moving in a like arcuate slot 178 but generally horizontally disposed, whereas the slots 173' and 176 are generally vertically disposed. This pin 177, in turn, is connected through a horizontally disposed link 179 to a corresponding pin 180 moving through a corresponding slot 181 and carried on a like projection on the right hand quantity counter shutter 5', which is, in turn, also connected to the right hand cost counter shutter 4' by a link and pin and slot construction similar to that just described in connection with the left hand shutter operating mechanism. Thus, it will be evident that the operating means for both sets of shutters 4', 5' will be simultaneously operated by the same mechanism which operates the clutch and brake mechanisms, so that the shutters will be positively closed at the beginning of the resetting operation and openable only at the end of the resetting operation, i. e. when the cam member 73 is returned to its initial position by the spring 75. Attention is further directed to the fact that, while the several pins and links are connected by cotter pins 182, the construction is such as to permit the several counter units 4 and 5 to be removed from the frame as units, upon merely withdrawing these cotter pins.

In Figures 20 to 22, I have shown a modified form of controlling and shutter operating mechanism which, while not preferred, may be used under certain conditions. In this construction, I have shown the shutter operating mechanism applied to a control mechanism of the general type described and claimed in my application Serial No. 716,696, but including certain of the improvements of the control mechanism described and claimed in my other application Serial No. 132,275. Here also it will be noted that the control mechanism and the shutter operating mechanism are shown in connection with a counting device of the type illustrated in the above mentioned applications rather than of the construction illustrated herein. Further, the structure has been illustrated in simplified form, only the control and shutter operating mechanism being shown, the several drives operating during counting and resetting being omitted to facilitate illustration.

As shown in these figures, a member 190 carried on the reset shaft 191 is operated in the usual manner and provided with a cooperating holding or non-return pawl 192 and a notch 193 adapted to cooperate with a pin 194 so that this pin will move out of the notch 193 at the beginning of resetting and travel around the periphery 195 of the member 190 during resetting and re-enter this notch when the cam has been moved through a complete resetting movement, mechanism also being provided for then moving the parts reversely through an additional 45 degrees, as described in my application Serial No. 132,275. As in my previous constructions mentioned, the cam member 190 is provided with a cam shoulder 196 and a ratchet shoulder 197 connected by a smooth peripheral portion 198 of reduced diameter, all of these being inwardly spaced from the periphery of the member 190. Herein, the pin 194 is carried on a member 194a of generally bell crank shape, rotatable on a stud 199 disposed above the resetting shaft 191. Further, as in the construction of my application Serial No. 716,696, a controlling cam member 200 is pivoted at 201 on the frame and provided with a hook 202 controlling a pin 203 on the block controlling swinging arm 204, corresponding to the arm 111 hereinabove described. This controlling cam member 200 is provided on its right hand end with a tail 204' adapted to be kicked out by the cam 196, and is also provided on its opposite end with a projection 205 adapted to engage the cam 196 after the tail 204 has been kicked out by that cam.

Here also it will be noted that a pivoted latch member 206 is pivoted at 207 on the frame above and to the left of the pivot 201, corresponding to the rebound preventing means heretofore described. This latch member has one arm extending laterally in such manner as to bias the latch by gravity to the position shown in Figure 22. It also has a tail 209 adapted to engage an abutment portion 210 on the left hand side of the lower arm of the member 194a, so that, as shown in Figure 22, as the pin 194 leaves the notch 193 and rides over the periphery 195 of the member 190, the hooked end 206 drops down by gravity to the position shown in Figure 22, wherein it prevents the escape of the pin 203, in such manner as to prevent a reverse movement of that member and of the swinging arm 204 which might otherwise release the blocks corresponding to the blocks 110, but not shown in Figures 20-22. Further, a pin 211 is provided on

a lateral extension on the lower arm of the bell crank member 194a, which pin is adapted to engage the upper surface of the tail 204' on the member 200 and thereby force the latter down when the pin 194 re-enters the notch 193, whereupon the pin 203 and the connected swinging block engaging arm 204, are actuated in such manner as to move the latter out of the path of the blocks and therefore condition the mechanism for resumption of counting. Here also a coiled spring 212 is connected to an upstanding projection on the upper arm of the bell crank member 194a and to a fixed point on the frame, in such manner as to be tensioned during resetting and, accordingly, to return the parts to their initial position at the completion of resetting, by moving the member 194a reversely through 45° in a known manner. It will be noted, however, that in this construction, as in that described in my application Serial No. 132,275, the reverse movement of the member 190 is through an angle of 45°, so that the advantages of such an increased range of movement described and claimed in my application Serial No. 132,275, are obtained herein.

Herein, note also that the tail 204' on the cam member 200 is herein provided with a depending link connection 213 connected through a slot and pin connection 214 with a bell crank latch 215, biased by a spring 216 and adapted to be thrown by this spring into engagement with a notch 217 on the pawl 192 to hold the latter out of engagement with the ratchet abutment 197. This holding out occurs while the parts are being moved by the spring 212 through the final 45° reverse movement, whereupon the link 213 is then lowered by the tail 204 to kick out the latch 215 and release the pawl 192 for engagement with the abutment 197. Thus, although the pawl 192 functions as heretofore to prevent reverse rotation of the reset shaft immediately following the beginning of resetting, i. e. immediately upon movement of the member 190 out of the position shown in Figure 20, this pawl 192 is held out of its holding position during the 45° reverse rotation of the parts, and only permitted to return to its normal position during counting, shown in Figure 20, at the end of this reverse movement.

Operatively connected in this control mechanism is also improved shutter operating mechanism generally similar to that heretofore described herein. This mechanism is controlled and actuated by the bell crank member or cam 194a and includes an elongated notch 220 on the left hand edge of the upper arm of that member. This notch provides abutments 221 and 222 at the opposite edges thereof and these are adapted to cooperate with a pin 223 projecting into the notch from a shutter operating member 224, which is of what may be called a walking beam type and also pivoted on the stud 199. Herein, this member 224 has one of its ends pivotally connected at 225 to a depending link 226 which is, in turn, pivotally connected at 227 to a backwardly extending arm 228 on the lower quantity counter shutter 229. Further, this arm 228 is connected between the shutter pivot 230 and the pin 227, by a pin 231 to an upwardly extending link 232 which is pivoted at 233 to the upper cost counter shutter 234, in turn, pivoted at 235. Similarly, the other end of the walking beam member 224 is connected through a separable longitudinal slot and pin connection 236 with a backwardly extending arm 237 on the upper

right hand cost counter shutter 238 pivoted at 239, and also connected through a depending link 240 with a backward extension 241 on the lower quantity counter shutter 242, pivoted at 243. Note also that a coiled spring 243 is connected between a lower part of the frame and the left hand arm of the member 224, which spring normally biases this member 224, and accordingly all of the shutters, to closed position. Thus, with the parts in the counting position shown in Figure 20 and with the shutters open, when resetting is started by rotation of the resetting shaft 191, the abutment 221 is moved away from the pin 223 on the arm 224, in such manner as to permit the spring 240 to pull down the arm 224, and thereby operate the two sets of linkages at the opposite ends of the member 224 to close all of the shutters. Further, when the bell crank cam member 194a is moved to the position shown in Figure 22 during resetting, it will be evident that the abutment 222 will engage the pin 223 if necessary, in order to insure a closing movement of the shutters. On the other hand, when at the completion of the resetting operation the abutment 221 is again raised, it will engage the pin 223 and thereby raise the left hand arm of the member 224 and, through the connections of the shutters to the opposite ends of this member, insure the opening of all of the shutters when the several counter reset shafts have completed their 45° reverse movement.

As a result of my improved construction, it is made possible while obtaining certain of the advantages of my previously mentioned applications, to produce a construction which is markedly improved in various respects. For example, it is possible to produce a construction wherein, although the connection of the counter units to their drives are definitely broken, due to the separation of the clutch elements, the drive is still held against movement, in such manner as effectually to eliminate difficulties due to the insertion of backlash during resetting and consequent error in the next counting operation. Further, it is made possible to decrease the load on the reset shaft and the effort required of the operator. Also, it is possible to increase the accuracy of the count under adverse conditions of operation, as, for example, by eliminating any possibility that the stop blocks will rebound and thereby insert error in the count, while the controlling mechanism is also such as to minimize the possibility of manipulation thereof to produce an inaccurate count. As a result of my improved construction, it is also made possible to obtain the advantages of resetting the several counters in a counting direction, and of utilizing both locked and internal transfer mechanism, while providing shutter mechanism on the counter units and providing removable counter units. Also, these improved units are carried on a single frame member in such manner as to permit ready withdrawal of these units longitudinally of their axes, and as complete entities, following disconnection of the shutter operating connections, by merely removing the cotter pins, one unit of each set being removable with its intermediate gears and their operating shaft and the other without these gears which, in this instance, remain connected to the frame 1. Further, the units are effectually enclosed in such an improved manner as to permit relatively rough handling of the same, while protecting the number wheels and internal mechanism from injury, and while yet enabling the units to be taken down quickly and

readily to permit access to the internal counter mechanism whenever desired. Attention is also directed to the improved shutter operating mechanism, not only operated in timed relation to the brake and clutch operating mechanism and from the swinging cam, but in such manner as to insure positive shutter operation in opposite directions at the proper times. Note also that I obtain an improved lost motion connection between the swinging cam and the shutter which makes it possible to obtain these results while continuing to obtain the long movement of the swinging cam necessary to obtain the desirable 45° reverse movement of the reset shaft, as shown in both the preferred and modified forms illustrated herein. Further, through my improved arrangement of separate counting and resetting drives, it will also be observed that the several driving trains are made readily accessible upon the removal of the counter units, while permitting the use of such separate drives and avoiding the difficulties incident to using a single drive for both resetting and driving the counters during counting. These and other advantages of my improved construction will, however, be clearly apparent to those skilled in the art.

While I have in this application specifically described two embodiments which my invention may assume in practice, it will be understood that these forms thereof are shown for purposes of illustration, and that the invention may be modified and embodied in other forms without departing from its spirit or the scope of the appended claims.

What I claim as new and desire to secure by Letters Patent is:

1. In a counting mechanism, a plurality of counters, driving trains therefor including a clutch having cooperating driving and driven elements, resetting mechanism including a resetting shaft having operative connections for resetting said counters, a reciprocable clutch operating member on said resetting shaft controlling both clutches, and cam means operated by said resetting mechanism for reciprocating said operating member.

2. In a counting mechanism, a plurality of counters, driving trains therefor each including a clutch having cooperating driving and driven elements, resetting mechanism including a rotatable resetting shaft having operative connections for resetting said counters, a reciprocable clutch operating member on said resetting shaft controlling said clutches, cam means operated by said resetting mechanism for reciprocating said operating member, and cooperating spring means acting on the driven elements of said clutches and reversely operating said clutch operating member.

3. In a counting mechanism, a plurality of counters, driving trains therefor each including cooperating friction clutch elements, resetting mechanism including a resetting shaft, means reciprocable on said resetting shaft for separating said clutch elements comprising a reciprocable clutch operating member, cam means operated by said resetting mechanism for reciprocating said operating member, cooperating spring means acting on the driven elements of said clutches and reversely operating said clutch operating member, and shippers normally pressed into engagement with said freely rotatable members by said springs and operable by said operating member to disengage said rotatable members.

4. In combination, a counter having a plurality

of operatively connected number wheels, a driving train therefor, resetting mechanism therefor including means for stopping an element in said driving train, and means for preventing rebounding of said element upon engagement with said stopping means.

5. In combination, a counter having a plurality of operatively connected number wheels, a driving train therefor, resetting mechanism therefor including means for stopping an element in said driving train, and means for preventing rebounding of said element upon engagement with said stopping means, said stopping means including an abutment on said element and a cooperating movable abutment controlled by said resetting mechanism and said rebound preventing means likewise engaging said abutment.

6. In combination, a counter having a plurality of operatively connected number wheels, a driving train therefor, resetting mechanism therefor including means for stopping an element in said driving train, and means for preventing rebounding of said element upon engagement with said stopping means, said stopping means including an abutment on said element and a cooperating movable abutment controlled by said resetting mechanism and said rebound preventing means likewise engaging said abutment, and means for releasing said stopping means while retaining said rebound preventing means in operation.

7. In combination, a counter having a plurality of operatively connected number wheels, a driving train therefor, resetting mechanism therefor including means for stopping an element in said driving train, and means for preventing rebounding of said element upon engagement with said stopping means, said element having an abutment thereon and said stopping means and rebound preventing means engaging opposite faces of said abutment.

8. In combination, a counter having a plurality of operatively connected number wheels, a driving train therefor, resetting mechanism therefor including means for stopping an element in said

driving train, and means for preventing rebounding of said element upon engagement with said stopping means, said resetting means including a resetting shaft and said stopping means and rebound preventing means both being rotatable about the axis of said shaft.

9. In combination, a counter having a plurality of operatively connected number wheels, a driving train therefor including an abutment carrying element, resetting mechanism therefor including means engaging said abutment to stop said element, and means for preventing rebounding of said element including a rotating abutment, said stopping means including a swinging stop arm engageable with said abutment and said rebound preventing means having an abutment engaging latch portion extending beyond the end of said arm and biased to abutment engaging position.

10. In combination, a counter having a plurality of operatively connected number wheels, a driving train therefor including an abutment carrying element, resetting mechanism having means for stopping said element in the zero position of the wheels, means for preventing rebound of said element when stopped, and means operative by said resetting mechanism for braking said drive and releasing the same while said rebound preventing means continues to operate.

11. In combination, a counter having a plurality of operatively connected number wheels, a drive train including a clutch having driving and driven elements, resetting mechanism including a reset shaft extending axially of said wheels and means for rotating said shaft reversely at the completion of resetting through an angle at least equal to that subtending each number space on said wheels, and means operative by said resetting mechanism for braking the driving element of said clutch and disconnecting the elements thereof during resetting and operative to reconnect said clutch and release said brake upon completion of said reverse movement of said shaft.

EDWARD A. SLYE.
